UNITED STATES PATENT OFFICE.

CHARLES EDWARD HOPKINS, OF WORCESTER, MASSACHUSETTS.

APPARATUS FOR FINISHING STEREO TYPE PLATES.

No. 877,775.

Specification of Letters Patent.

Patented Jan. 28, 1908.

Application filed October 28, 1907. Serial No. 399,465.

To all whom it may concern:

Be it known that I, CHARLES EDWARD HOPKINS, stereotyper, a citizen of the United States, residing at 578 Pleasant street, Worcester, Massachusetts, United States of America, have invented certain new and useful Improvements in Apparatus for Finishing Stereotype-Plates, of which the following is a specification.

10 This invention relates to improvements in apparatus or an improved apparatus for trimming and finishing curved stereotype plates and while it is especially adapted for use in conjunction with a curved stereotype casting apparatus of the type described in my prior British Patent No. 15314 of 1905, still it (or certain parts of it) may also be used in conjunction with any other suitable kind or type of apparatus for casting curved 20 stereotype plates. In apparatus of this kind it is important that the plates should be cast, trimmed, and finished (ready for placing in the printing machine) in the shortest time possible, but a certain amount of time is 25 necessarily lost in allowing the stereotype plate to cool before it is taken from the casting chamber and whereas the main body of the plate cools comparatively quickly the riser or slug owing to its thickness takes 30 longer to solidify throughout its mass and it is impossible to cut this riser or slug off and trim the plate until it is solid as there is a danger of liquid metal running down over the convex surface of the plate and spoiling 35 the impression thereon.

Now according to the present invention I remove the cast plate from the casting chamber as soon as it is sufficiently cool so to do and carry it in a receiver to a special trimming cylinder where it has its concave surface shaved previous to its riser or slug being cut off, so that this latter has plenty of time to solidify throughout its mass. In addition this invention comprises an entirely new and 40 improved trimming and finishing apparatus automatically connected up and working so that all the steps of the operation are performed without the necessity of hand work. Moreover where quickness is so important 45 it is an advantage to perform the operation of cutting off the riser etc. away from the casting chamber and not as in my aforesaid prior patent during the act of removing the plate as this cutting operation takes some

time *i. e.* about four seconds, whereas otherwise the cast plate can be more quickly removed and hence the casting chamber the sooner prepared for the next casting operation.

I will not attempt to describe the casting operation as this operation is well-known nor does it form, nor does the apparatus therefor form, any part of my present invention; but will pass on to the description of the mechanism, its connections and movements from the point at which, the casting being complete, the casting chamber is opened, until the point at which the cast plate is delivered ready for putting into the printing machine; and in order that my invention may be readily understood I will describe it with reference to the drawings I have annexed hereto in which it is shown in conjunction with an upright rotatable core casting mechanism but it must be understood that these drawings illustrate only one method of carrying out my invention, the full scope whereof may readily be gathered from the description together with the statement hereinbefore contained.

Figures 1 and 1^X when taken together show side elevational views of the casting chamber receiver and the finishing cylinder with the apparatus and connections for operating the same. Fig. 2 shows a plan view of the whole apparatus. Fig. 3 shows a back sectional view of the receiver and its connections on line D—D of Fig. 2. Fig. 4 shows a back elevational view of the finishing cylinder and its connection. Figs. 1^a, 1^b and 1^c show the guide plate 122 (Figs. 1 and 2) in plan, side and end views respectively. Figs. 1^d and 1^e show the guide block 123 (Fig. 1) in side and plan views respectively. Fig. 2^a shows the yoke clamping mechanism 314 (Fig. 2) in plan view. Fig. 4^a shows a section through Fig. 4 on the line a—a while the cast plate is being shaved. Fig. 4^b shows a section of Fig. 1 on the line b—b. Fig. 4^c shows in detail the riser ejecting apparatus (Fig. 4). Fig. 4^d shows cam 302 and roller 306 (Fig. 4) and its operation. Fig. 4^f shows the cam disk 316 (Fig. 4) in plan view.

In the following more detailed description the same numerals indicate the same parts throughout.

After a casting has been made the opera-

tor pushes down on the drag operating handle 1 (Fig. 1) thereby starting to withdraw the segmental back 2 away from the stereotype plate cast in the casting chamber 5 formed between the cylinder 5 and back 2 (Figs. 1 and 2); simultaneously with which action the flexible matrix is gradually separated from the stereotype casting 3 formed upon the periphery of the cylindrical core 5; 10 as soon as the back is moved sufficiently to entirely separate the matrix from the stereotype a projecting arm 6 (Fig. 2) attached to the lower end of the back causes a pivoted pawl 7 to engage a rock-arm 8 attached to a slide-piece 9 (which operates in a guide-way in upper part of the base box B) which in turn is connected to a clutch mounted upon the main driving shaft 200 through the rock-arm 10 attached to the upright rock 20 shaft 11 and rock yoke 12 operating in the sliding collar of the clutch mechanism 13; a further backward movement of the drag causes the rock-arm 8 to withdraw the spring-actuated stop 14 from engagement 25 with the stop 15 attached to the lower end of the cylindrical core 5 (Figs. 2 and 3) the withdrawal of this spring actuated stop allows the spring 16, which has been held compressed, to expand thereby moving the 30 sliding jaw of the clutch up into engagement with the jaw fixed upon the main driving shaft 200; instantly upon the engagement of the clutch the core is started to revolve thereby carrying the stereotype 3 out of the 35 casting chamber; as the cylinder finishes a half revolution a second stop 17 engages the spring-actuated stop 14 thereby causing (by the inverse action above-described) the movable jaw of the clutch 13 to become disengaged when the cylinder comes to a full stop 40 with the casting in position as shown in Figs. 1, 2 and 3. The operator now proceeds to move the back 2 up and into position against the core 5 when the projections 45 70, 70 and 61 attached to the back will engage the stereotype cast and force it away from the periphery of the core and over the supports 18, 18, 18, 18 (Fig. 2) into and onto the segmental receiver A; simultaneously 50 with the ejection of the stereotype from the core the riser end of the stereotype (which projects above the receiver A) engages projections 113 pivoted on the receiver so as to operate the supporting arms 111 to which are 55 attached the clamping projections or bars 110 (Fig. 1) and forces the bars 110 to separate and allow the stereotype to pass by over the guide-ways 18 into position in the receiver when projections 113 and 110 will be 60 moved over the straight edge of the stereotype casting by springs 114, 114 (Figs. 1 and 3) mounted upon the receiver A and the stereotype will therefore be firmly locked in the receiver.

As the projection 113 is pressed back on 65 moving the stereotype into position in the receiver as aforesaid an arm 115 (Figs. 1 and 2) which is attached to one of the lower supporting arms 111 is forced from engagement with the operating lever 116 connected with 70 the sliding collar of the clutch 118 through the link 117, when the spring 119 which has been held at tension forces the jaws of the clutch into working engagement thereby 75 throwing into operation the finishing mechanism; a rock-arm 204 to which is attached the cam roller 203 operating in a groove in cam 202 mounted on the cycle shaft 201 (Fig. 2) is connected to the receiver A through a link 205 operative on a 80 shaft 206 (Figs. 2 and 3) rigidly fixed to the lower end of the receiver A and the shaft 206 in turn is held in position and guided, also 85 operates through a guide-plate 122 (Figs. 1^a, 1^b and 1^c) loose on the shaft 206 and a guide-block 123 (Figs. 1, 1^a and 1^c) keyed or fixed to the shaft, one end of the guide-block being formed into a sector gear having a suitable number of teeth 224 to cause the receiver A to make a half revolution when 90 passing over the rack 225 fixed to the base B (which as shown in Fig. 1 is broken away so as to clearly show the mechanism under and in it).

A guide-way 220 (Fig. 2) is formed in the 95 base B through and in which the guide-plate 122 operates and supports the receiver, additional guide-ways 226 (Fig. 4) are arranged at each end of the way into which the guide-block 123 enters after the receiver has made 100 a half-turn and locks the receiver firmly into position owing to the guide-block being rigidly fixed to the receiver shaft 206.

Attached to the bottom ends of the pivots upon which are mounted the supporting arms 105 111 of the clamps 110 are short links 100 (Figs. 2 and 3) united by a bar 101 to which is pivoted a roller 102 which when the receiver is moved up into position against the cylinder C, on completion of the operation of 110 shaving is engaged by a cam plate 103 attached to the lower end of the finishing cylinder. This cam-plate is positioned so as to operate upon the roller 102 immediately the stereotype has been shaved thereby unlocking the locking clamps 110 from off the straight sides of the then shaved stereotype and allowing the stereotype to move with the revolving cylinder as hereafter described.

Having described the ejecting of the cast 120 from the casting chamber and the mechanism by which the receiver locks and holds the stereotype in position, also the means by which the receiver conveys the stereotype to the finishing cylinder I will now proceed to 125 describe the mechanism for finishing the stereotype.

As the receiver A comes into position with

the finishing cylinder C suitable locking arms 300 (Figs. 1, 2 and 4^a) are made to engage depressions 301 formed on the outside-face of the receiver as follows: Supported on upright shafts 303, 303 are locking arms 300, 300, 300, and 300 (Figs. 1 2 and 4^a) at the lower end and under the base plate are two arms 304, 304 connected together and attached to a forked shaft 305 (Fig. 4^a) having 5 a roller 306 pivoted to it and positioned so as to operate in the groove of the cam 302 and so timed that the instant the receiver comes into position against the cylinder the cam groove forces the roller outwards thereby 10 throwing through the connection the locking arms 300 into engagement with the depressions 301 in the receiver A and firmly locking the said receiver into position so that the stereotype held therein can be shaved during 15 the next half revolution of the cylinder as hereinafter described.

Mounted in an upright position within the base is what I term a cycle shaft for the reason that it makes only one revolution for 20 each cycle of movements necessary to convey, finish and deliver a stereotype plate. This cycle shaft 201 has mounted upon it a large gear 250 the upper surface of which has formed upon it a miter gear 251 which when 25 in operation is driven through miter gear 253 (Figs. 1 and 2) attached to the main driving shaft 200. Meshing in with gear 250 is gear 252 (Figs. 1 and 4) which is mounted upon the shaft of the finishing cylinder C and being 30 only one-half the size of gear 250 it makes two revolutions to one of that by which it is driven. The finishing cylinder is made in this case of a size to fit against the inside 35 surface of the stereotype plate between the raised ribs and having depressions turned 40 into its face suitable for allowing the ribs cast upon the stereotype to enter; by this means the stereotype is always solidly held against the face of the finishing cylinder during the 45 trimming operations.

One side of the cylinder is made with a 50 depression 311 (Figs. 2 and 4^a) which not only forms a place for the shaving knife 312 but also a clearance for the shavings of metal 55 as they are removed from the stereotype ribs. This clearance in this particular design of machine need only extend a sufficient length to allow of a knife long enough to shave all the ribs cast upon the stereotype.

Pivottally attached to the upper end of the 60 finishing cylinder and one to each side are curved bands or clamps 313, 313 (Figs. 1, 2, 4 and 2^a) being connected by links and cross-bar 314 on which is mounted a roller 315 which operates in a cam groove formed in 65 cam 316 axially alined with the cylinder but fixed to the frame-work K so as to hold it stationary while the cylinder revolves thereby causing the bands 313 to clamp the

stereotype after being shaved and carry it 65 along with the cylinder and thereafter unclamp the severed riser as it is being ejected as hereinafter described. Also attached to the upper end of the cylinder is the slug 70 ejector consisting of a spring-actuated plate 317 (Figs. 1, 4^b and 4^c) so placed that it can be moved away or towards the cylinder surface; this ejector is connected to a cross-rod operating through a hole in the cylinder shaft; at the other end of the rod is a coil 75 spring 318 always under tension when the ejector plate is pressed into or against the cylinder, the face of which is recessed the thickness of the ejector plate so as to allow the face of the plate to be approximately 80 flush with the cylinder surface when closed in; also attached to the cross-rod supporting the ejector plate 317 is an upright arm having a roller 339 mounted upon the upper end operating upon a cam face 340 in the 85 fixed cam wheel 316 (which has two separate cam grooves) so that as the cylinder revolves carrying the stereotype around with it (and through the trimmers hereinafter described) it is so timed that the instant the stereotype 90 leaves the trimmers the roller 339 (Fig. 4^c) leaves the cam face, which act releases the tension on the spring 318, which causes the ejector to shoot forward and force the riser over the edge of the guide-ways 350 which 95 are so formed as to carry the severed riser away from the cylinder and out of the path of the finished stereotype below. As the cylinder continues to revolve the roller 339 is drawn back by the cam face 340 and 100 returns the ejector into position against the face of the cylinder.

The trimming cutters of which I illustrate two (Fig. 4) 319 and 320 are fixed to a shaft 322 which is held in operative position by a 105 bracket 321 fixed to the top surface of the base plate B by bolts or by other suitable means; the said trimmers and shafts are connected to a short shaft 323 operating through the base B; and to the lower end 110 of the said shaft is fixed a driving belt pulley 324; this pulley 324 is driven at a high rate of speed from pulley 400 mounted upon upright power connecting shaft 401 (Fig. 2) through a belt connection 402. The 115 trimmers 319 and 320 are formed with a bevel of approximately 45° and have projecting cutting edges 325 which enter grooves or clearances 326 cut into the face of the cylinder C (above and below the 120 shaving knife 312), said trimmers also entering through clearances 326^a (Fig. 4) in stop piece 331 attached to the periphery of cylinder C opposite to that side of the cylinder C into which the shaving knife 312 is 125 inserted—said stop piece 331 extending the length of the stereotype as cast; this stop piece 331 engages the shaved stereotype the

instant it is released by the locking clamps 110 on receiver A, and simultaneously, the clamps 313 (attached to the cylinder C) engage the riser end of the stereotype; by 5 these combined means the stereotype (after being shaved) is carried around by the cylinder C so that the trimmers may engage it and cut the necessary bevels on the curved ends of the stereotype and simultaneously 10 sever the riser—after which the finished stereotype is pushed along by the stop-piece 331.

For the purpose of guiding the stereotype as it is being ejected from the cylinder I 15 provide arms 328 having fingers 329 attached to one end which project into suitable grooves 330 cut in the finishing cylinders face there are also clearances cut into the shaving knife and stop-piece in line with 20 the grooves 330 so that the fingers may remain at all times in the grooves, means are also provided for supporting the arms 328, 328, in proper position consisting of an upright shaft 332 fixed to the base plate B.

25 Mounted upon the trimmer brackets 321 are flexible brackets supporting anti-friction rollers 340 which operate on the bevels cut into the stereotype by the trimmers 319 and 320, the purpose for which these anti-friction rollers are employed is to support the stereotype during and just after the trimmers have ceased to operate. I place the rollers upon flexible supports so that they can give slightly as the stereotype is 30 being freed from the surface of the cylinder C and pushed upon the finished stereotype receiving platform 327 which is mounted upon the base B and made to extend around one side of the finishing cylinder nearly as 35 far as the trimming cutters as well as project sufficiently far away from the cylinder to hold the ejected stereotype 3 shown in Fig. 2.

In order that this invention may be the better understood I will now describe the 45 complete cycle of operations from the time the plate is cast in the casting chamber until it is delivered trimmed and finished.

When the cast plate in the casting chamber which is formed between the rotating 50 core 5 and the drag 2 (Figs. 1 and 2) is sufficiently cool, the handle F (Fig. 1) is depressed towards the left, thereby drawing the drag 2 from the core 5 (Fig. 2). When the drag 2 has moved sufficiently to cause 55 the matrix to be detached from the cast plate the pivoted pawl 7 carried on the arm 6 catches against the rock-arm 8 borne on the slide 9. Further movement causes the arm 8 to raise the spring stop 14 out of contact 60 with the stop 15 and this allows the spring 16 to push the lock yoke 12 against the sliding collar of the clutch 13, whereby the slide 9 is moved towards the left and the core 5 is rotated from the shaft 200 through its bevel 65 gear wheels.

The pivoted pawl 7 and the rock arm 8 are moved out of engagement and then the spring stop 14 resumes its normal position. The core 5 continues to rotate until the stop 17 comes in contact with the spring stop 14 70 (i. e., through 180°) when the stop 14 and the slide 9 are pushed towards the right (Fig. 2) i. e., into their original position, this causing the rock-yoke 12 to be pressed back against the spring 16, thus throwing the sliding collar of the clutch 13 out of gear and stopping the rotation of the core 5. The apparatus then remains in this position, i. e., as shown in Fig. 2, with the cast plate opposite the receiver A, until the back 2 is 80 moved up against the core 5 for a fresh casting operation; this movement of the drag 2 causes the fingers 61 to push the cast plate off the core 5 on to the guide-ways 18 and into the receiver A, and when the cast plate 85 is in the receiver A the projections 113, 110, 110 grasp the straight sides of the plate through the action of the springs 114, 114, and the arms 111 (Figs. 2 and 3).

The act of pressing the cast plate into the 90 receiver A forces the projections 113 to separate owing to their engaging the face of the riser of the stereotype which movement causes the arms 115 attached to one of the lower arms 111 operated by the projection 95 113 to become disengaged from the operating lever 116 thereby releasing the spring on the clutch 118 through which the finishing mechanism is thrown into operation. The apparatus starting in the position as shown in Fig. 2, on the cast stereotype being moved into the receiver A and the clutch 118 thrown into operation the cycle wheel 250 is 100 revolved until the cam roller 203 arrives approximately at the point Z in the cam groove 202. The cylinder C is then in the position shown in Fig. 2 and the effect of a quarter revolution of the cycle wheel 252 will be to draw the receiver A by means of the said cam 203, the cam groove 202 and the pivoted lever 204 up to the finishing cylinder C, the said receiver A being rotated during its movement from the core 5 up to the cylinder C through 180° by means of the rack 225 and teeth 224; the cylinder C is at 115 the same time rotated through 180° when the arms 300, 300, are thrown into the grooves 301, 301 by the action of the cam roller 306 working in the groove 302 and through the medium of the arm 304 and links 305; during the next quarter revolution of the wheel 252 the receiver is held in this locked position (with the cast plate firmly fixed therein by means of the projections 115 and 110) while the knife 312 is moved over 120 its concave surface thereby shaving the ribs of the same.

On starting the next quarter revolution of the wheel 252 the arms 300, 300, are thrown out of the grooves 301, 301, (by the 125

reverse action above described) and the arms 313, 313, through the action of the cam roller 315 in the fixed cam disk 316 (Fig. 4) and the yoke 314, are made to grasp 5 the riser of the cast plate; the cam piece 103 attached to the bottom of the cylinder C simultaneously engages the roller 102 operating the clamping bars 110 which have held the stereotype fast in the receiver A and 10 moves the clamping bars away so that the stereotype is free to rotate along with the cylinder C past the knives 319 and 320 (Fig. 4) whereby the riser is cut off and the edges trimmed and beveled, during which operation 15 the receiver has been moving towards the core 5. At the beginning of the next quarter revolution of the wheel 252 the riser is pushed and started down the chute 350 by means of the plate 317, the spring 318 and 20 the cam 339 (Fig. 1).

In the middle of the last quarter revolution of the wheel 252 the receiver A is brought up against the core 5 when the operation is stopped through the clutch 118 being thrown 25 out of gear. On the next plate being pushed into the receiver this quarter revolution is completed until the cam roller 203 again comes approximately to the point Z in the cam groove 202. During this last quarter 30 revolution the cast stereotype is removed from the cylinder C by the action of the arms 328 and fingers 329 and is moved on to the platform 327.

I provide the lever 116 with flexible end 35 piece which is capable of yielding to the arm 115 as the receiver A is moved away from the core.

Although my invention is as aforesaid particularly adapted for use in conjunction 40 with such apparatus for casting curved stereotype plates as has an upright rotatable core yet it is evident that it (or certain parts thereof) may be applied to other suitable forms of curved stereotype casting apparatus.

45 What I claim is:—

1. In an apparatus for finishing stereotype plates, the combination of means for holding a plate, a finishing cylinder having means for shaving the inside of said plate, means for 50 revolving said cylinder, devices for finishing the ends of said plate, and means whereby said cylinder after shaving the inside of said plate carries along with it the plate to be trimmed by the finishing devices, substantially as described.

2. In an apparatus for finishing stereotype plates, the combination of a cylinder carrying a shaving knife, means for revolving said cylinder, devices for holding a plate so that 60 said shaving knife will operate upon its interior, means for releasing said plate when the shaving operation is completed, means for trimming the ends of said plate, and means carried by said cylinder for removing said

plate along with said cylinder to subject said plate to the action of the trimming devices after the shaving operation has been completed, substantially as described.

3. In an apparatus for finishing stereotype plates, the combination of a cylinder provided with a shaving knife, means for revolving said cylinder, means for holding a plate against said shaving knife, means for trimming the ends of said plate, gripping means carried by said cylinder for engaging said plate after the shaving operation has been completed, and means carried by said cylinder for releasing the plate from the holding means and causing it to be engaged by the gripping means as soon as the shaving operation is completed, substantially as described.

4. In an apparatus for finishing stereotype plates, the combination of a cylinder provided with a shaving knife, means for revolving said cylinder, means for holding a stereotype plate in contact with said knife, gripping means carried by said cylinder for engaging said plate when the shaving operation is finished, means for trimming the ends of said plate, devices operated by the revolution of said cylinder for disengaging said holding means from said plate and for bringing said gripping means into engagement with said plate when the shaving operation is finished, and means for disengaging the finished plate from said cylinder, substantially as described.

5. In an apparatus for finishing stereotype plates, the combination of a cylinder provided with a shaving knife, means for holding said plate against said cylinder, means for trimming the ends of said plate, including devices for cutting off the riser at the upper end of said plate, and means for ejecting the 100 cut off portion from the machine, including a plate, a spring actuated rod carrying said plate, and a cam attached to the cylinder and engaging said rod and controlling its action, substantially as described.

6. In an apparatus for finishing stereotype plates, the combination of a finishing cylinder provided with a shaving knife, said cylinder and knife being provided with grooves, disengaging fingers adapted to engage said 105 grooves, means for revolving said cylinder, means for holding a plate in contact with said shaving knife, means for disengaging said holding means, means for gripping the upper end of said plate when disengaged 110 from said holding means, said gripping means being carried by said cylinder, and means for trimming the ends of said plate, substantially as described.

7. In an apparatus for finishing stereotype plates, the combination of a cylinder provided with a recess, a shaving knife set in said recess, means for revolving said cylinder

der, means for holding a plate against said shaving knife, means for disengaging said holding means when the shaved portion is finished, means operated by said cylinder 5 for gripping said plate when so released, and devices for trimming off the ends of said cylinder, substantially as described.

In witness whereof I have hereunto set my hand in presence of two witnesses.

CHARLES EDWARD HOPKINS.
